[57] CLAIM

The ornamental design for a novelty bottle opener, as shown and described.

DESCRIPTION

FIG. 1 is a front perspective view of the novelty bottle opener according to my design;

FIG. 2 is a bottom plan view of the novelty bottle opener according to FIG. 1;

FIG. 3 is a rear, end elevational view of the novelty bottle opener according to FIG. 1;

FIG. 4 is a front, end elevational view of the novelty bottle opener according to FIG. 1; and,

FIG. 5 is a side elevational view of the novelty bottle opener, the side opposite being a mirror image.

FIG. 1

FIG. 2

FIG. 3

FIG. 4

FIG. 5
